UNITED STATES PATENT OFFICE.

CHARLES J. AHRENFELDT, OF NEW YORK, N. Y.

DESIGN FOR A PLATE OR SIMILAR ARTICLE.

SPECIFICATION forming part of Design No. 31,707, dated October 24, 1899.

Application filed March 3, 1899. Serial No. 707,675. Term of patent 31 years.

To all whom it may concern:

Be it known that I, CHARLES J. AHRENFELDT, a citizen of the United States, residing at the city of New York, county of New York, 5 and State of New York, have invented and produced a new and original Design for a Plate or Similar Article, of which the following is a specification, reference being had to the accompanying drawings, forming a part hereof, 10 and like letters referring to like parts in each figure of the same.

In the said drawings, Figure 1 is a plan view of a plate with my design placed thereon. Fig. 2 is a medial vertical section of the same.

15 In the design upon the plate, A is a cluster of roses A' with leaves A² interspersed, surrounded by the foliate scrolls A³, A⁴, A⁵, and A⁶.

B consists of a cluster of roses B' supple-

mented by stems B² bearing leaves, and a 20 foliate scroll B³ above the same.

C is a rose C' bordered by leaves within a wreath C², which appears to be suspended by a ribbon C³, having a knot at its center.

The piece B is situated between A and C, 25 and the three pieces of ornament are repeated a number of times to form a band or border.

This design may be applied to articles other than plates.

What I claim is—

30 The design for a plate or similar article substantially as herein shown and described.

Signed at the city of New York, in the State of New York, this 10th day of February, 1899.

CHARLES J. AHRENFELDT.
